CLAIM

The ornamental design for a beverage machine, as shown and described.

DESCRIPTION

FIG. 1 is a top, front, left side perspective view of a beverage machine according to our new design;

FIG. 2 is a left side elevation view thereof;

FIG. 3 is a top plan view thereof;

FIG. 4 is a front elevation view thereof;

FIG. 5 is a right side elevation view thereof;

FIG. 6 is a rear elevation view thereof;

FIG. 7 is a bottom plan view thereof; and,

FIG. 8 is a top, front, right side perspective view thereof. The broken lines illustrate portions of the beverage machine that form no part of the claimed design.

1 Claim, 4 Drawing Sheets
